UNITED STATES PATENT OFFICE.

WILLIAM M. THAWLEY, OF TORONTO, CANADA.

DESIGN FOR AN ADVERTISING-SIGN FOR TROLLEY-POLES.

SPECIFICATION forming part of Design No. 29,641, dated November 8, 1898.

Application filed April 1, 1898. Serial No. 676,148. Term of patent 14 years.

To all whom it may concern:

Be it known that I, WILLIAM MARCY THAWLEY, a citizen of the United States, residing at Toronto, in the county of York and Province of Ontario, Canada, have invented and produced a new and original Design for an Advertising-Sign, of which the following is a specification, reference being had to the accompanying drawings.

10 Figure 1 is a fragment of a panel, partly in section. Fig. 2 is a perspective view of the panel.

Like letters of reference refer to like parts throughout the specification and drawings.

15 D represents a tubular frame for the advertising-sign. Depending from the under side of the frame D is a partition F.

G G represent two sets of guides, one set located at each side of the partition F. Each set of guides G consists of an inwardly-bent 20 piece of metal extending around the borders of the partition and forming with the partition a substantially U-shaped slide.

What I claim is—

The design for an advertising-sign for trolley-poles as herein shown and described.

Toronto, March 16, A. D. 1898.

W. M. THAWLEY.

In presence of—

J. E. CAMERON,
M. A. WESTWOOD.
